E. C. RANKS, OF BOSTON, MASSACHUSETTS.

Letters Patent No. 87,111, dated February 23, 1869.

IMPROVED RECLINING-CHAIR.

The Schedule referred to in these Letters Patent and making part of the same.

To all whom it may concern:

Be it known that I, E. C. RANKS, of Boston, in the county of Suffolk, and State of Massachusetts, have invented an Improvement in Reclining-Chairs; and I do hereby declare that the following, taken in connection with the drawings which accompany and form part of this specification, is a description of my invention sufficient to enable those skilled in the art to practise it.

The invention relates particularly to the construction of that class of reclining-chairs, in each of which the seat-frame, the back-frame, the foot-frame, and the arms are jointed together, the seat moving slightly forward, and the arms back, as the sitter moves from upright sitting posture to a reclined position, the improvement having particular reference to the construction and arrangement of mechanism for locking the parts in any position into which they can be brought by the occupant of the chair, and consisting, primarily, in combining with the swinging back and foot-piece, or frames, a notched latch-bar, which rests, by gravity, against a pin, with which its notches engage, the bar being hinged, at its front end, to the leg or foot-frame, in such manner as to be moved forward and back by the forward and back movements of this frame, the bar sliding freely forward or back, when raised by a lever-arm at the end of a shaft projecting through the stationary cross-piece at the side of the chair, (which shaft bears a knob, by turning which the latch-bar is raised,) and dropping into engagement with the stop-pin at any point, when released from the hand of the occupant of the chair.

The drawings represent the frame-work of a reclining-chair embodying my invention.

A represents a vertical section, showing the parts in place for a person to sit in upright position.

B is a vertical section, showing the chair "extended."

a denotes the stool, or stationary part of the chair, composed of the legs b, side rails c, and cross-bars d.

e denotes the swinging frame, which supports the feet and legs when the chair is extended.

f is the swinging back, or back-frame.

The back is pivoted at bottom to the side rails c, by pins g, and the frame e to the rails c by pins h, the frame f swinging freely back, and the frame e freely forward, on their respective pivots.

Just below each two pivot-pins g h, one of the side rails i of the chair-seat is hung to the frames e f, as seen at A, while above the pins g h, the opposite ends of each arm k are hinged to the respective frames, as seen at A and B, the arms and seat, and the front and back frames having, by their connections, a simultaneous movement, as will be readily understood, the chair, as respects the arrangement and movement of all these parts, being not materially unlike other reclining-chairs in common use.

To one of the side pieces of the frame e, I hinge a notched or toothed latch-bar, l, the bar swinging loosely on its hinge, and extending back through a slot in a guide-plate, m, through which extends a cross-pin or shaft, n, which, projecting through the adjacent stationary side rail, has fixed upon its end a knob, o, by means of which rotative movement is imparted to the pin.

Upon this pin the latch-bar rests by gravity, the pin entering the notch above it, and acting as a stop, to arrest longitudinal movement of the latch-bar, thereby locking the back and leg-frames f e in any position into which they have been carried by movement of the occupant of the chair.

The latch-bar is made thicker above the notches, or with a shoulder, p, against which the end of an arm, q, on the pin n, acts, to lift the bar from engagement with the pin when the knob o is turned by the hand of the occupant, the latch-bar sliding freely upon this arm when so raised, thereby enabling the chair to be more or less inclined by movement of the body, the latch-bar falling, upon release of the knob, and arresting and locking the chair in position, as before described, preventing movement of the frames e and f in either direction.

It will be seen that this locking and releasing-mechanism is exceedingly simple and effective, requiring less than a quarter turn of the knob to lift and release the latch, while it locks itself.

The hinge-plate r, to which the latch-bar is jointed, extends across the end of the side piece of the frame e, as seen in the drawings, it being fastened to the frame by screws. In this, and in a slotted bar which is similarly applied in some other chairs, the strain upon the leg-frame, by pushing it forward with the feet, (when the frame is locked in position,) is apt to start the screws and loosen the plate. To obviate this, I extend a strap-piece, s, from the hinge-plate r, and angular thereto, as seen at B, fastening this by a screw, (or by screws,) which, extending into the frame-piece at nearly a right angle to the other screws, securely holds the hinge-plate, so that it cannot be drawn off or loosened by strain.

I claim, in combination with the swing-frames e f, the shouldered notched latch-bar l, locking-pin n, and lifting-lever q, constructed and arranged to operate together, in the manner and for the purpose substantially as described.

I also claim, in combination with the hinged locking-bar l, the angular strap piece r s, applied substantially as shown and described.

E. C. RANKS.
